UNITED STATES PATENT OFFICE.

LELAND D. HARRIS, OF SALT LAKE CITY, UTAH.

LOUD SPEAKER.

Application filed June 12, 1926. Serial No. 115,523.

This invention relates to sound reproducing devices of that type known as loud speakers, and has for one of its objects to improve and simplify the general construction of devices of this character and to provide one that will be exceedingly sensitive to weak electrical currents and will emit soft, natural and mellow tones.

With the foregoing and other objects in view, the nature of which will become apparent as the description proceeds, the invention consists of the construction, combination and arrangement of parts herein-after fully described and claimed, and illustrated in the accompanying drawings, wherein:

Figure 1 is a bottom plan view of a sound reproducing device constructed in accordance with my invention,

Figure 2 is a sectional view taken on the vertical planes indicated by the lines 2—2 of Figure 1,

Figure 3 is a detail view of the electromagnet of the device,

Figure 4 is a sectional view taken on the plane indicated by the line 4—4 of Figure 3,

Figure 5 is a sectional view taken on the plane indicated by the line 5—5 of Figure 4,

Figure 6 is a sectional view taken on the plane indicated by the line 6—6 of Figure 4,

Figure 7 is a detail perspective view of the pole pieces of the permanent magnets of the device,

Figure 8 is a detail perspective view of the armature and armature supporting frame of the electromagnet, and

Figure 9 is a detail perspective view of the core of the spool of the electromagnet.

Corresponding and like parts are referred to in the following description, and designated in the several views of the accompanying drawings, by similar reference characters.

In the drawings, 1 designates the case of the sound reproducing device. This part consists of a body member 2 and a cap member 3 which are connected together by screws 4. The cap member 3 is provided with a hollow stud 5 which projects centrally therethrough and is externally screw threaded to permit a horn, not shown, to be connected thereto. The inner wall or throat 6 of the stud 5 tapers inwardly. A diaphragm 7 is secured to and between the case members 2 and 3 and is maintained out of direct contact therewith by a rubber gasket 8. The

diaphragm 7 is circular and is provided with corrugations 9 which are arranged concentrically with respect to each other and to the center of the diaphragm and which gradually increase in size from the center toward the edge of the diaphragm.

Semi-circular and permanent magnets 10 and 11 are secured to the case member 2 by screws 12. The magnets 10 and 11 are arranged with their like poles in opposed relation, and secured by the screws 12 to the ends of the magnets are pole pieces 13 and 14. The pole piece 13 is secured to the magnets 10 and 11 at one side thereof, and the pole piece 14 is secured to the magnets at the opposite side thereof. The pole pieces 13 and 14 extend inwardly from the magnets 10 and 11 and gradually decrease in width in the direction of their inner ends. The outer ends of the pole pieces 13 and 14 are provided with air gaps 15, and the inner ends 16 of these parts are of U-form and arranged in opposed relation.

An electromagnet 17 is arranged within and supported by the pole pieces 16, and said pole pieces present a north and south magnetic pole at each side of the electromagnet. The electromagnet 17 comprises a coil 18 which is mounted upon a spool consisting of a metal core 19 and sides 20 of bakelite or other suitable insulating material. Lugs 21 carried by the core 19 and contacting with the outer faces of the sides 20, retain these parts and the coil 18 in assembled relation.

A frame 22 is removably positioned in the core 19, and is provided with shoulders 23 which contact with the core 19 to limit the extent of its insertion into the core. An armature 24 is rockably supported within the frame 22 by a spindle 25, and is provided with an apertured extension or lug 26 which fits in a corresponding extension 27 of the frame 22. A link 28 connects the armature 24 to the diaphragm 7, and this part is secured to the lug 26 and to the center of the diaphragm. The pole piece ends 16 contact with the frame 22 and with the sides of the spool, and as the result hold the electromagnet 17 against casual movement. The frame 22 is of greater thickness than the armature 24 in order to permit the free movement of the latter. The pole piece ends 16 are positioned to one side of the center of the device so as to permit the link 28 to be arranged in the axis of the diaphragm 7. The terminals 18 of the coil 18 are secured

2 to binding posts 29 carried by a terminal block 30 which is secured by screws 31 to the end 16 of the pole piece 13.

- This device may be connected to the electrical reproducer for phonograph records forming the subject-matter of my copending application, filed the 12th day of June, 1926, and serially numbered 115,524. This connection may be established by leads extending from the reproducer to the binding posts 29. The currents thus caused to traverse the coil 18 will vibrate the armature 24 in accordance with their varying intensity. The vibrations of the armature 24 will be transmitted to the diaphragm 7 through the link 28, and the vibrations of the diaphragm will, due to its corrugations 9, and the formation of the throat 6 of the stud 5, produce soft, natural and mellow tones.
- It should be understood that the drawings are merely illustrative and do not pretend to give exact proportions. Furthermore, the said drawings are illustrative of a preferred construction, it being my expectation that various changes and modifications may be made without departing from the spirit and scope of my invention.

What is claimed is:—

1. A sound reproducing device comprising a diaphragm, arcuate permanent magnets, pole pieces arranged diametrically of the magnets and having their outer ends secured to the opposite sides of the magnets, the inner ends of the pole pieces being of substantially U-form and arranged in op-

posed relation within the magnets, a coil located within the inner ends of the pole pieces, a frame extending through and beyond the coil and engaged by the inner ends of the pole pieces to secure it and the coil in place, an armature arranged within and rockably supported by the frame, and an element connecting the armature to the diaphragm.

2. A sound reproducer comprising a diaphragm, a permanent magnet, pole pieces connected at their outer ends to the magnet and having inner ends of substantially U-form, a coil located within the inner ends of the pole pieces, an open frame extending through and beyond the coil and engaged at points beyond the coil by the inner ends of the pole pieces to secure it and the coil in place, an armature arranged within and rockably supported by the frame, and an element connecting the armature to the diaphragm.

3. A sound reproducing device comprising a diaphragm, a permanent magnet, pole pieces connected to the magnet, a coil associated with the magnet, sides for the coil, a hollow core passing through the coil and sides and provided with lugs contacting with the outer faces of the sides, an armature rockably supported within the coil, and an element connecting the armature to the diaphragm.

In testimony whereof I affix my signature.

LELAND D. HARRIS.
